Primary Examiner — Doris Clark*(74) Attorney, Agent, or Firm* — Dickstein Shapiro LLP(57) **CLAIM**

The ornamental design for an electric deterrent device, substantially as shown and described.

DESCRIPTION

FIG. 1 is a front perspective view of an electric deterrent device showing my new design;

FIG. 2 is an end view thereof;

FIG. 3 is an end view thereof (the opposite end of FIG. 2);

FIG. 4 is a right side view thereof;

FIG. 5 is a left side view thereof; and,

FIG. 6 is a top view thereof.

The bottom view is unornamented and/or unclaimed, and is therefore not provided. The broken lines are for illustrative purposes only and form no part of the claimed design.
